UNITED STATES PATENT OFFICE

95,097

DESIGN FOR A SHOE

Willy Weidner, New York, N. Y., assignor to
Frank Litvack, Lynn, Mass.

Application January 17, 1935, Serial No. 54,889

Term of patent 3½ years

To all whom it may concern:

Be it known that I, Willy Weidner, a citizen of the United States, residing at 47 West 34th Street, New York, in the county of New York and State of New York, have invented a new, original, and ornamental Design for a Shoe, of which the following is a specification, reference being had to the accompanying drawing, forming a part thereof, in which

The figure is a view in perspective of a shoe showing my new design, the heel being conventional and shown in dot and dash lines.

The ornamental effect of my design resides in a toe cap having its rear edge bound with a

stitched band, and a centrally disposed member composed of wide, flat, open-center ovals stitched about both edges and overlapping where they are joined, said member permanently retaining its shape and extending upwardly from the toe tip, being located symmetrically above the sole and being narrower than the sole.

I claim:

The ornamental design for a shoe substantially as shown and described.

In testimony whereof, I have affixed my signature hereto.

WILLY WEIDNER
